United States Patent Office

Des. 202,329
Patented Sept. 21, 1965

202,329

GLOVE

George Swistel, Trenton, N.J., assignor, by mesne assignments, to International Latex Corporation, Dover, Del., a corporation of Delaware

Filed Apr. 23, 1964, Ser. No. 79,665

Term of patent 14 years

(Cl. D3—11)

Fig. 1.

Fig. 2.

Fig. 3.

Fig. 4.

Fig. 5.

I claim:

The ornamental design for a glove, as shown.
